DESIGN FOR A RIBBON

John D. Huizeng, New York, N. Y.

Application December 11, 1939, Serial No. 88,799

Term of patent 7 years

To all whom it may concern:

Be it known that I, John D. Huizeng, a citizen of the United States, residing in New York city, in the county of New York and State of New York, have invented a new, original, and ornamental Design for a Ribbon, of which the following is a specification, reference being had to the accompanying drawing, forming part thereof.

Fig. 1 is a plan view of a ribbon showing my design, and

Fig. 2 is the reverse side thereof.

The design comprises an ombréed ribbon consisting of a wide, dark center stripe, bordered on each side by two relatively narrow, lighter shaded stripes, one of faille and one of satin, said faille stripes being moiréed, all as shown.

I claim:

The ornamental design for a ribbon, substantially as shown and described.

JOHN D. HUIZENG.
